UNITED STATES PATENT OFFICE.

GEORGE H. MIDDLEMISS, OF BIRMINGHAM, ALABAMA.

SWITCH-CONTROLLING DEVICE.

Application filed June 21, 1923. Serial No. 446,885.

This invention relates to an automatic switch controlling device, its object being to control the closing of a main switch to which it is attached, making the switch an automatic reclosing switch and providing in the device itself a "trip free" mechanism.

A further object is to provide means for remote control of both the opening and closing of any switch apparatus, said means being of simple character and design to dispense with the present solenoid operating mechanism commonly used with remote control switches, and thereby to eliminate expensive storage batteries and auxiliary apparatus of this character common in large sub-stations.

One important object of the invention is to provide an improved apparatus wherein a switch, opened through the action of an over-load or other like means may be automatically closed after a predetermined timed interval.

A second important object of the invention is to provide an improved arrangement of this character, wherein the closing of the switch may be effected, either manually or automatically as desired.

A third important object of the invention is to provide an improved mechanism wherein both the opening and closing of the switch may be controlled either manually or automatically.

With the above and other objects in view as will be hereinafter apparent, the invention consists in general of certain novel details of construction and combinations of parts hereinafter fully described, illustrated in the accompanying drawings and specifically claimed.

In the accompanying drawings, like characters of reference indicate like parts in the several views, and:

Fig. 1 is a side view of the form of apparatus adapted for use for both automatic and manual opening and closing of the switch, the outlines of a well known type of main switch being illustrated above, and the apparatus itself being shown in its relation thereto below.

Fig. 2 is an enlarged plan view of this form of the apparatus.

Fig. 3 is an enlarged detail side elevation showing the parts in a second position in full lines, and in a third position in dotted lines, the dotted lines disclosing certain of the

parts in their position when the main switch is open.

Fig. 4 is a detail view of a certain latch mechanism used in connection herewith, a trigger forming part of this mechanism being shown in position of engagement in full lines, and in position of release in dotted lines.

Fig. 5 is a view of the parts shown in Fig. 4 in the position they assume when the switch is open, and just prior to the restoration of the latch to the normal position indicated in full lines in Fig. 4.

Fig. 6 is a detail section on the line 6—6 of Fig. 4.

Fig. 7 is a detail section on the line 7—7 of Fig. 2 and showing the gearing arrangement.

Fig. 8 is a diagrammatic view disclosing the wiring of this form of the invention.

Fig. 9 is an enlarged plan view of a somewhat modified and simplified form of the device arranged for automatic opening under overload conditions and automatic closing.

Fig. 10 is a side view of this modified form of the device.

Fig. 11 is a diagrammatic view of this form of the device showing a typical wiring arrangement adapted for use in connection therewith.

Fig. 12 is a detailed section of one of the solenoids.

In the construction of the device as shown in Figs. 1, 2 and 3, it will be seen that there is disclosed a main switch 10 of well known type, this switch being normally closed and actuated through the medium of a lever 11 and rod 12 which connects to the switch control apparatus proper. This switch control apparatus is mounted on a base 13 which is in turn mounted on a suitable foundation 14, this foundation having at one end a spring pit 15. On the base 13 is mounted a pair of bearings 16 wherein is journaled a shaft 17 on which is keyed a worm wheel 18. This worm wheel 18 is engaged by a worm 19 carried on the shaft of a motor 20. On the shaft 17 is also provided a pinion 21 which meshes with a large gear 22 fixed on the cam shaft 23 of the device, this shaft being mounted in bearings 24 carried on the base 13.

Pivottally mounted on the shaft 17 is a pair of lever arms 25 which carry at their ends a pin 26 supporting a plate 27 to which

is secured the upper ends of a set of springs 28, the lower ends of these springs being secured to a plate 29 embedded in the foundation 14, the purpose of this arrangement being to provide for proper length of the springs. These springs are tension springs and normally urge the ends of the bars 25 to which they are attached downward. Spaced from the shaft 17, the arms 25 are connected by a slug shaft 30 whereon is mounted a roller 31. Fixed on the shaft 23 is a spiral cam 32, the roller 31 and cam 32 co-acting in such manner that operation of the motor 20 will serve to rotate the cam in the direction of the arrow in Fig. 3, and thus cause raising of the lever arms 25. A second pair of lever arms, which I will term for distinction the trip arms 33, are also provided on the shaft 17 and extend toward the spring end of the main lever arms 25. These trip lever arms lie between the main lever arms and are provided adjacent their forward ends with downwardly extending arms 34 between the lower ends of which is pivoted a trigger 35 so positioned as to engage a roller or stop 36 carried by bearings 37 extending upward from the base 13. Extending between the trip lever arms 33 is a pin 38 to which is pivoted the lower end of the rod 12. These parts are so arranged that when the trip lever arms 33 are in their downward position, the trigger 35 will engage the roller 36 and hold these arms downward. Furthermore, with the trip lever arms in their downward position, as shown in Fig. 1, and in full lines in Fig. 3, the switch 10 is closed.

Extending from the trigger 35 is an arm 39, and beneath the end of this arm is located a plunger 40 surrounded by a solenoid coil 41, the arrangement being such that energization of the solenoid will cause lifting of the plunger 40, so that the trigger 35 will be freed from its roller or stop 36. Under these conditions, the switch 10 will open by gravity. A spring 42 normally serves to hold the trigger 35 in roller engaging position but yields, upon the depression of the arms 33, to permit the trigger to move around the roller 36 into its engaging position. The ends of the arms 33 are connected by a pin 43 whereon is mounted a trigger 44 adapted for engagement by a roller 45 carried on a pin 46 connecting the arms 25. This trigger 44 is normally held in roller engaging position by means of a suitable compression spring 47 as shown, this spring pressing down on an arm 48 which, when the arms 33 are in locked down position, lies over the solenoid plunger 40 so that the operation of this solenoid plunger not only frees the trigger 44 from the roller 45 in the event that the arms 25 are in their depressed position but also disengages trigger 35 from roller 36, as hereinbefore explained, permit-

ting arms 33 to move upward. Beneath the free ends of the arms 25 is located a dash pot 49 and connected to said arms is a piston rod 50 carrying a piston 51 operating in said dash pot. The arms 25 are also extended away from the springs beyond the shaft 17 and between these ends of the arms, which are preferably termed the rear ends, is located a roller 52 adapted for engagement by a locking trigger 53 pivoted between bearings 54 on the base 13, and provided with an arm 55 extending over the plunger 56 of a solenoid 57. A stop loop 58 serves to limit the movement of the trigger 53.

Before considering further the remainder of the apparatus, we will now follow the operation of the portion which has just been described. Normally the main lever arms are in the position shown in Fig. 1, that is to say, their rear ends are locked down and their front ends raised so that the springs 28 are under tension. At this time the cam 32 is in such position that release of the trigger 53 will permit these arms 25 to drop downward. It is to be noted that the arms 33 are bent so that these arms may also be locked down while the rear end of the arms 25 are locked down. Under these conditions, suppose the solenoid 41 to be energized; its core 40 will raise and will engage the arms 39 and 48, thus releasing the trigger 35 from the roller 36 whereupon the arms 33 will rise to the dotted line position in Fig. 3 through the action of the gravity biased switch 10. These arms will remain in this raised position until the solenoid 57 is energized, whereupon the trigger 53 will release from the roller 52, and the springs 28 will pull the arms 25 downward and carry with them the arms 33 thus closing the switch. However, if the solenoid 41 still remains energized, the arm 48 will contact with the solenoid core 40 as the arms 33 come down, and the trigger 44 will release from the roller 45 so that the arms 33 will again fly up and will then remain up until the cam 32 has been revolved by the action of the motor 20 to such position that the roller 45 engages the trigger 44. So long as the solenoid 57 remains energized the arms 25 will alternately rise and fall, but if the solenoid be deenergized the movement of the arms 25 downward under the influence of the spring 28 will carry down the arms 33 and these arms will lock down by reason of the engagement of the trigger 35 with the roller 36. Then upon the next upward movement of the arms 25, the trigger 53 will engage the roller 52 and lock these arms in their raised position ready for the next cycle of operations.

It will be obvious that the solenoids 41 and 57 may be controlled in a variety of ways, either manually or automatically, and as an example of the manner in which

said control may be obtained, reference may be had to Fig. 8. In this figure, it will be seen that there is provided a pair of main line wires 59 and 60. The current flowing through these wires is controlled by the main switch 10. These line wires are connected by wires 61 with the primary winding of a transformer 62. The motor 20 is here shown as a commutator motor but it may be of any preferred type.

On the shaft 23 is mounted a contact wheel having an insulating segment 63, and a conductor segment 64. A pair of brushes 65 bear on this contact wheel, and one of these brushes is connected by a wire 66 with the motor 20, the other brush being connected by a wire 67 with the secondary winding of the transformer 62. The remaining brush of the motor is connected by a wire 67' with the secondary winding of the transformer 62. Also the wire 66 is connected by a wire 68 with a spring contact 69 fixed on the standard of the bearing 16. From this contact 69 a rod 70 extends upward through a bar 71 mounted on the arms 25. On the rod 70 is a stop collar 72 against which the bar 71 engages upon downward movement of the rear ends of the arms 25. There is also provided a contact 73 wherewith the contact 69 engages when the springs 28 draw the arms 25 downward. This contact 73 is connected by a wire 74 with the wire 67.

In series in the line wire 60 is the solenoid winding 60' of an overload relay having a movable contact 60^a arranged to be moved, upon overload energization of the solenoid winding, into engagement with the contacts 60^b and 60^c. From the contact 60^c a wire 76 leads to a battery 75. The battery 75 is also connected by a wire 78 with the solenoid 41, the other end of the winding being connected by a wire 79 with the overload relay contact 60^b. Thus, when the overload relay is operated by an overload, a circuit will be closed from the battery 75 through the wire 76, contact 60^c, contact 60^a, contact 60^b, wire 79, solenoid winding 41, and wire 78 back to the battery. Consequently, the solenoid winding 41 will be energized and the latches or triggers 35 and 44 will be moved to permit the arms 33 to rise and the switch 10 will open. With the cam in the position shown in Fig. 3, it will be observed that one of the contact fingers 65 rests on the insulating segment 63 so that no current can flow through these contact fingers. Furthermore, with the arms 25 in the position shown in Fig. 1, contact will be broken between the contacts 69 and 73. Consequently, under these conditions, the switch 10 will remain open even though the overload relay contacts be opened, and the battery circuit interrupted.

In order to actuate the solenoid 57 one end

of the winding of this solenoid is connected by a wire 80 with the battery 75, through the wire 76, the other end of said winding being connected by a wire 81 with the wire 78 through a switch 82. Now it will be seen upon closing of the switch 82 the solenoid 57 will be energized and the trigger 53 moved to released position so that the springs 28 will operate to depress the front ends of the arms 25 and bring down the arms 33, thus closing the switch 10. At the same time this movement of the arms 25 will permit closing of the circuit through the contact 69 and 73, and in consequence current will flow from the transformer 62 through the wire 67, wire 74, contact 73, contact 69, wire 68, motor 20, wire 67' and transformer 62. This will cause operation of the motor, and the consequent rotation of the cam. This rotation of the cam will raise the arms 25 and the raising of these arms will, toward the end of the movement, break the circuit between contact 73 and 69, but at this time, both of the contact fingers 65 will be on the conductor segment 64, and the revolution of the cam will continue until one of these fingers has passed on to the insulating segment 63, this movement taking place when the cam is in position to allow free dropping of the roller 31.

However, unless the solenoid 57 be energized by the closing of the switch 82 the arms 25 will be held raised so that the parts will again assume the position shown in Fig. 1. On the contrary, so long as the solenoid 57 is energized, the arms 25 will alternately rise and fall.

Furthermore, means may be provided, in some instances, whereby the solenoid 41 may be under the control of an operator at the switchboard or other distant station. To this end there may be provided a wire 83 which leads to a manually controlled switch 84, a wire 85 leading from the stationary contact of this switch to the wire 79. Under these circumstances, when the switch 84 is closed, current will flow from the battery through the wire 80, wire 83, switch 84, wire 85, wire 79, solenoid 41 and wire 78 back to the battery 75. Thus closing of the switch 84 will energize the solenoid 41, and trip the trip levers 33 so that they open the switch 10.

In the remaining form of the device, as shown in Figures 9, 10, and 11, it will be seen that the device is substantially that just described with certain of the parts omitted, these parts including the trigger 35 and its associated elements, the trigger 53 and its associated elements. The operation of this form of the device and its wiring connections are, however, to a certain extent different and while the same reference characters are used for those parts which are alike in the two, certain variations

occur in the wiring which will now be described.

In Fig. 11, it will be noted that the wire 67 does not lead as in Fig. 8, but is connected to an automatic switch reclosing device 72 operated by the shaft 23 and the details of which are disclosed in my co-pending application, bearing the Serial Number 581,749, which was filed on the 14th day 10 of August, 1922. From this resetting apparatus the wire 74 leads to the contact 73. With this arrangement overload on the line wires 59 and 60 beyond the switch 10, the abnormal current through the solenoid winding 60' closes the overload relay as before, and the arms 33 rise and the switch 10 opens, as described in reference to Fig. 8. The upward movement of the arms 33 permits closing of contact between contacts 69 20 and 73, and thus starts the motor 20 which, by the action of the cam 32, raises the lever 25. When this lever reaches its uppermost position, the trigger 44 is engaged by the roller 45. Thereupon, further movement of 25 the cam permits the lever 25 to drop under the influence of spring 28 and the arms 33 are pulled downward and close switch 10. If the overload no longer persists, the arms 33 are held down and the switch is held 30 closed since downward movement of these arms breaks the motor circuit and the movement of the cam stops. If overload still persists the overload relay again operates to trip the trigger 44 and the operation is repeated for the second closing of the switch 10. If the overload still persists after the second closing of the switch and its being again opened, further reclosing movement will be stopped through the action of the 40 cutout switch forming part of the apparatus indicated at 72 as described in the aforesaid copending application, this occurring, of course, if the cutout is set for two consecutive operations of the switch. It will thus be seen that this form of the device is especially adapted for use in connection with the device of the application aforesaid whenever the same is used to control oil switches 45 which are not in themselves equipped with trip free mechanism.

It will now be seen that with this arrangement closing of the switch 10 will take place with each downward movement of the actuating arms 25, and alternately opening 50 and closing of said switch will continue so long as the overload circuit breaker remains open, since the energization of the solenoid 41 will cause tripping of the trigger 44 with each movement of the actuating or resetting arms downwardly. Also as soon as the overload circuit breaker 61 can be closed and remain closed, or in other words, as soon as the overload has passed from the line wires, the switch 10 will be closed and held 55 closed since the solenoid 41 will be de-ener-

gized and its plunger will not affect the trigger 44.

Returning now to the first form of the invention, it is desirable that the trigger 44 be held in such position as to freely pass the 70 roller 45 from the time when the solenoid 41 acts to trip the tripping levers 33 until the switch 10 is fully open, and these trip levers 33 reach their highest position. This is because of the possibility of the actuating 75 arms or levers 25 moving downwardly at the instant when it is desirable that the trip levers 33 should move upwardly. To this end provision is made to lock the trigger 44 in its disengaging position during upward 80 movement of the trip lever arms 33, and to release the trigger so that it may assume its normal position upon completion of this upward movement. The means for doing this are shown in Figures 4, 5 and 6, wherein the 85 spring 47 is omitted in order to show the remaining parts more clearly. By an inspection of these figures, it will be seen that an arrow-headed lug 94 depends from the head 95 of the connecting rod 12, and from the arm 48 extends upwardly a pair of notched spring arms 96 which engage the lug 94 upon the arms 48 being raised, thus assuming the position shown in dotted lines in Figure 4. Now, as the trip arms 33 rise, 90 they will move angularly with respect to the rod 12. Consequently, the arrow-headed lug 94 will swing laterally in the position shown in Fig. 5 whereupon the spring arms 96 will be released from the lug 94, and the 95 trigger 44 allowed to resume its normal position with respect to the arms 33.

There has thus been provided a simple and efficient device of the kind described and for the purpose specified.

It is obvious that minor changes may be made in the form and construction of the invention without departing from the material spirit thereof. It is not, therefore, desired to confine the invention to the exact 100 form herein shown and described, but it is desired to include all such as properly come within the scope claimed.

Having thus described the invention, what is claimed as new, is:

1. A circuit including a main switch, an operating mechanism for the main switch including a trip lever and means actuated by an overload on the main switch for tripping the trip lever to open the main 110 switch, and resetting mechanism including an oscillating lever operable to effect resetting of the trip lever engageable with and disengageable from the trip lever, motor means to oscillate the resetting lever, said 120 motor means including an auxiliary means normally tending to move the resetting lever in one direction and to impart an initial movement to said lever, means actuated by the initial movement of the re- 130

setting lever for energizing the motor means, and means controllable by load conditions in the circuit and controlling the mutual engagement and disengagement of said levers 5 and also the initial movement of the resetting lever.

2. A circuit including a main switch, an operating mechanism for the main switch including a trip lever and means actuated 10 by an overload on the main switch for tripping the trip lever to open the main switch, and resetting mechanism including an oscillating lever operable to effect resetting of the trip lever engageable with and dis- 15 engageable from the trip lever, motor means to oscillate the resetting lever, said motor means including an auxiliary means normally tending to move the resetting lever in one direction and to impart an initial 20 movement to said lever, means actuated by the initial movement of the resetting lever for energizing the motor means, means controllable by load conditions in the circuit and controlling the mutual engagement and 25 disengagement of said levers and also the initial movement of the resetting lever, and retarding means for controlling the action of the oscillating lever.

3. A circuit including a main switch and 30 an overload relay, a trip lever connected to the main switch, latch means for the trip lever normally holding the lever in position to hold the main switch closed, means actuated by the closing of the relay for effect- 35 ing release of the latch means, a resetting lever for moving the trip lever in resetting direction carrying an element coacting with the latch means, motor actuated means oper- 40 able by overload conditions in the circuit for moving the resetting lever into position for engagement by the latch means, other means for moving said resetting lever in the opposite direction to cause switch clos- 45 ing movement of the trip lever, and means actuated by the initial movement of the re- 50 setting lever for energizing the motor of the motor actuated means.

4. A circuit including a main switch and 55 an overload relay, a trip lever connected to the main switch, latch means for the trip lever normally holding the lever in position to hold the main switch closed, means actuated by the closing of the relay for effecting release of the latch means, a re- 60 setting lever carrying an element coacting with the latch means, motor actuated means operable by overload conditions in the circuit for moving the resetting lever into position for engagement by the latch means, 65 other means for moving said resetting lever in the opposite direction to cause switch closing movement of the trip lever, means actuated by the initial movement of the re- 70 setting lever for energizing the motor of the motor actuated means, and other latch means

releasable under overload conditions in the circuit for restraining the trip lever from movement to open the main switch.

5. A circuit including a main switch and an overload relay, a trip lever connected to 70 the main switch, latch means for the trip lever normally holding the lever in position to hold the main switch closed, means actuated by the closing of the relay for effecting release of the latch means, a reset- 75 ting lever carrying an element coacting with the latch means, motor actuated means operable by overload conditions in the circuit for moving the resetting lever into position for engagement by the latch means, other 80 means for moving said resetting lever in the opposite direction to cause switch closing movement of the trip lever, other latch means releasable under overload conditions in the circuit for restraining the trip lever 85 from movement to open the main switch, means actuated by the initial movement of the resetting lever for energizing the motor of the motor actuated means, and means to retard the switch closing movement of the 90 levers.

6. A circuit including a main switch and an overload relay, a trip lever connected to the main switch, latch means for the trip lever normally holding the lever in position to hold the main switch closed, means actuated by the closing of the relay for effecting release of the latch means, a resetting lever carrying an element coacting with the latch means, motor actuated means operable by overload conditions in the circuit for moving the resetting lever into position for engagement by the latch means, other means for moving said resetting levers in the opposite direction to cause switch clos- 100 ing movement of the trip lever, means actuated by the initial movement of the re- 105 setting lever for energizing the motor of the motor actuated means, and other latch means releasable under overload conditions in the 110 circuit for restraining the trip lever from movement to open the main switch, and electrically controlled trip means to hold the re- 115 setting lever against trip lever actuating movement.

7. A circuit including a main switch and an overload relay, a trip lever connected to the main switch, latch means for the trip lever normally holding the lever in position to hold the main switch closed, means actuated by the closing of the relay for effecting release of the latch means, a resetting lever carrying an element coacting with the latch means, motor actuated means operable by overload conditions in the circuit for mov- 120 ing the resetting lever into position for engagement by the latch means, other means for moving said resetting lever in the oppo- 125 site direction to cause switch closing move- 130 ment of the trip lever, means actuated by

- the initial movement of the resetting lever for energizing the motor of the motor actuated means, other latch means releasable under overload conditions in the circuit for 5 restraining the trip lever from movement to open the main switch, a remote manual control for said latch means, and electrically controlled trip means to hold the resetting lever against trip lever actuating movement.
- 10 8. A circuit including a main switch and an overload relay, a trip lever connected to the main switch, latch means for the trip lever normally holding the lever in position to hold the main switch closed, means actuated 15 by the closing of the relay for effecting release of the latch means, a resetting lever carrying an element coacting with the latch means, motor actuated means operable by overload conditions in the circuit for moving 20 the resetting lever into position for engagement by the latch means, other means for moving said resetting lever in the opposite direction to cause switch closing movement of the trip lever, means actuated by the initial 25 movement of the resetting lever for energizing the motor of the motor actuated means, other latch means releasable under overload conditions in the circuit for restraining the trip lever from movement to 30 open the main switch, means to retard the switch closing movement of the levers, and electrically controlled trip means to hold the resetting lever against trip lever actuating movement.
- 35 9. A controlling mechanism for a main switch biased to open position, including in combination with a trip lever connected to the switch, of a resetting lever and a stationary stop, a plurality of trip mechanisms carried 40 by the trip lever one of which is cooperative with the resetting lever to hold the trip lever and the other with said stop, and means operative by an overload to release said tripping means from said stationary 45 stop and the resetting lever.
10. A controlling mechanism for a switch, including in combination with a trip lever connected to the switch, of a resetting lever engageable with the trip lever, means 50 to hold the resetting lever and through the resetting lever the trip lever in position to hold the switch closed, tripping means to connect the trip lever to the resetting lever and a stationary stop and tripping means 55 to connect the trip lever with the stationary stop, and means operative by an overload to release both tripping means and allow the switch to open.
11. A controlling mechanism for a main switch biased to open position, including 60 in combination with a trip lever connected to the switch and a resetting lever pivotally connected to the trip lever, of tripping means operative to connect the resetting lever with the trip lever, a stationary stop and tripping mechanism carried by the trip lever to engage said stop, and means operative by an overload to release said tripping means from said stationary stop and the resetting lever.
12. A controlling mechanism for a switch, including in combination with a trip lever connected to the switch, of a resetting lever with both levers being operative on a common pivot, means to hold the resetting lever and through the resetting lever the trip lever in position to hold the switch closed, tripping means to connect the trip lever to the resetting lever, a stationary stop and tripping means to connect the trip lever with the stationary stop, and means operative by an overload to release both tripping means and allow the switch to open.
13. A controlling mechanism for a switch normally biased to open position, including 75 in combination with a trip lever and connections to the switch, of a resetting lever, both levers being operable in parallel planes and the resetting lever engageable to the trip lever to hold the switch in closed position, means to operate the resetting lever, a trip for holding the resetting lever in inoperative position, means to release the trip from the resetting lever and means to disengage the trip lever from the resetting lever.
14. A controlling mechanism for a switch normally biased to open position, including 80 in combination with a trip lever and connections to hold the switch closed, of a resetting lever engageable to the trip lever to hold the switch in closed position and releasable to allow the switch to open, a spring means to operate the engaged resetting and trip levers, a trip for holding the resetting lever in inoperative position, electrically operated means to release the trip from the resetting lever and electrically operated means to disengage the trip lever from the resetting lever.
15. In testimony whereof I hereunto affix my 90 signature.
- GEORGE H. MIDDLEMISS.
